UNITED STATES PATENT OFFICE.

RUFUS POPE, OF NOBESVILLE, NEBRASKA, ASSIGNOR OF ONE-HALF TO
W. H. B. STOUT, OF SAME PLACE.

CARPENTER'S SQUARE.

SPECIFICATION forming part of Letters Patent No. 257,515, dated May 9, 1882.

Application filed January 17, 1882. (No model.)

To all whom it may concern:

Be it known that I, RUFUS POPE, a citizen of the United States of America, residing at Nobesville, in the county of Lancaster and State 5 of Nebraska, have invented certain new and useful Improvements in Carpenters' Squares; and I do hereby declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 My invention relates to certain improvements in carpenters' squares, hereinafter described, and specifically set forth in the claims.

Figure 1 represents the face side of a square embodying my improvements; Fig. 2, the reverse side thereof, and Fig. 3 a detail illustration of one manner of using the square.

Like letters refer to like parts in all the figures.

A represents the usual measure, divided into 25 inches and subdivisions thereof; B, a board-measure table of usual characteristics.

C is a protractor, of usual arrangement in itself; but in this instance it is located with its center on the twelve-inch mark, and continued 30 or coincidentally slanted lines D are formed upon the face of the tongue portion of the square, each of said lines being marked with the name indicating the particular geometrical figure of which it constitutes a side when used in the 35 manner hereinafter described.

At the end of the main or principal portion 40 of the square, and upon its face, is marked, stamped, or formed a table of geometrical figures, and the angles of the inclination of their sides, internal and external. On the reverse side of the tongue are formed, marked, or stamped slanting lines E, having indicating marks showing the relative slant of each line from a base-line, and expressed in inches to 45 foot, as clearly shown, and also in degrees. These lines are for use in cutting or laying out the bevels of braces, batter-posts, rafters, &c., whereby these may readily and without tedious computation be produced in what is known

as "one-half pitch," or any other relative bevel 50 to one-sixth pitch, &c.

By the use of the lines D any geometrical figure up to one having twelve sides may with equal readiness be produced or laid out.

It is evident that the occasions for the use 55 of the improvements above described are numerous in drafting, laying out frame-work, and in constructing regular and irregular cabinet and other work, and the saving of time connected with their use is one of the principal 60 benefits arising therefrom.

I am aware that protractors are not new, nor the specific manner of using them herein set forth, and I do not claim such as of my invention; but the manner of adapting the common 65 steel square by the particular arrangement herein shown I believe to be novel and useful.

The manner of using my square is as follows: To lay out any geometrical figure—for instance, an octagon—draw the base-line *e f*, place the 70 square No. 1 on the line, as shown, and draw the line *g c*. By consulting the lines D it will be seen that the octagon-line terminates at 5". Therefore place the square No. 3 at five inches from the base-line on the line *g c* and at 75 12" on the line *e f*, and draw the line *a b*, which is one of the sides of the octagon. Now reverse the square to the position occupied by square No. 2, mark the point *d*, and draw the line *b d*. Lay out another line *g c*, and repeat the operation until the eight sides are produced. To 80 lay out rafters, &c., place the main blade of the square against the lower side of the rafter and carry out or continue by marking across the contiguous side the slanted line *E*, which 85 bears the indication of the desired pitch in inches to foot—for instance, five inches between twenty degrees and twenty-five degrees—and remove the square and continue said line in the opposite direction, so that it 90 shall extend entirely across said side, said last continuation being over that portion covered by the square in the first instance, and the line thus marked is at right angles to a perpendicular line through the apex of the roof. In like 95 manner braces and batter-posts may be laid out.

Having described my invention and the

manner of using the same, what I claim as new, and desire to secure by Letters Patent, is—

A square bearing upon its face side and tongue lines coincident with those of a protractor centrally located on its blade, and indicating marks designating the geometrical figure of which each line forms a unit or side, and also marks indicating the internal and ex-

ternal angles of said figures, substantially as shown and described.

In testimony whereof I have affixed my signature in presence of two witnesses.

RUFUS POPE.
